[57] ABSTRACT

A catching device for use with a ski to prevent its running away upon becoming loose from the foot of the skier comprising an axle, a yoke fixedly mounted on the axle for rotation therewith and having a shank portion extending beyond the axle at both sides thereof, a spring biasing the axle and the shank portion thereby in a direction which is transverse to the general direction of the running surface of a ski, when the catching device is mounted on a ski, and pointing downward from the running surface, thereby engaging the snow and braking the movement of the ski.

DEVICE FOR CATCHING A RUNAWAY SKI

The present invention relates to a device for catching a runaway ski which becomes loose after the fall of a skier.

BACKGROUND OF THE INVENTION

In order to avoid loss of a ski after the safety binding thereof has opened when the skier fell, practically all present-day bindings are provided with safety straps. Such straps are loosely bound around the ski boot so that the ski, even after the binding has opened, remains connected with the skier and cannot free itself completely. Consequently, other skiers on the slope would become endangered, or the ski would become lost especially on steep terrains with obstructed view.

The disadvantage of such safety straps resides in that, in case of a fall, they pull on the ski which became loose from the boot and during a fall at high speed it might powerfully rebound back against the skier and injure him with its sharp edges.

In order to avoid such accidents it has been proposed to completely omit the safety straps so that the ski could remove itself from the immediate area of the skier after a fall. Instead of safety straps there has been proposed a catching device which after the safety binding has opened, becomes automatically operated and will bring the ski to a stop by a cable suspension after a short distance so that the skier can again reach his skis. One of such known devices comprises essentially a braking lever which is spring-biased and is mounted on the upper surface of the ski in front of the ski binding and which is held in its inactuated position by means of a projection protruding under the ski boot. As soon as the binding opens up and the ski boot lifts itself out of the binding, the spring causes a rotation of the aforementioned lever and thereby to protrude over the longitudinal side edge of the ski into a perpendicular plane with respect to the running surface of the ski, whereby a portion of the lever will dig itself into the snow and force the ski to come to a stop after a certain time.

This device possesses different disadvantages. As mentioned above it is mounted in front of the ski binding where the present-day bindings are usually provided with a swiveling head which in the event of a fall swivels sideways and thereby protrudes at least with a portion thereof over the side edge of the ski. As a result it gets into the swiveling region of the catching device mentioned above which is also protruding over the edge of the ski. Therefore, the catching device, that is its lever, can under certain circumstances interfere with the swiveling head of the safety binding and thereby be prevented from becoming operational.

A further disadvantage of such known catching device resides in that its lever which is being pressed down by the ski boot exercises a substantial pressure through its associated spring against the nose of the boot against which it abuts and thereby increases the frictional forces operating on the boot. As a result, a reliable functioning of the front piece of the safety binding cannot be expected since it is a basic requirement that the nose of the boot should free itself easily from the swiveling head of the safety binding.

Furthermore, it has been found that such a device which is operable only along a longitudinal edge of the ski, on packed snow or especially on icy slopes, cannot

be fully effective since the ski is lifted off the ground on only one side thereof by the braking lever which is in a vertical position with respect to the ski. Therefore, a large portion of the weight of the ski becomes shifted on the opposite edge thereof and remains unimpeded.

SUMMARY OF THE INVENTION

It is, therefore, an object of the present invention to 10 eliminate the above-described disadvantages associated with known catching devices.

It is a further object of the present invention to provide a novel catching device for a runaway ski which is capable of stopping the runaway ski after a relatively 15 short distance or immediately after the fall under any snow conditions prevailing on the ski slope.

According to the present invention a shaft or axle is 20 provided transversely on the upper surface of the ski and on which a pair of rearwardly projecting shank portions are journaled which under the effect of a spring are easily transferred into a catching or operational position in which they protrude substantially vertically 25 downwardly from the running surface of the ski, and which are connected with a yoke portion pointing in the opposite direction with respect to the axle and which operates to help to retain the shank portions in an inactuated position when the ski boot is safely in the 30 binding, the entire catching device being mounted on the ski in the back of the ski boot.

Such a catching device must naturally be capable of 35 cooperating with all types of safety bindings and accommodate the different types of bindings by undergoing only minor modifications.

BRIEF DESCRIPTION OF THE DRAWINGS

The invention will become more readily apparent 40 from the following description of preferred embodiments thereof shown in the accompanying drawings, in which:

FIG. 1 is a side view showing the catching device according to the present invention mounted on a ski having a safety binding of a first type, the catching device being shown in its rest or inactuated position;

FIG. 2 illustrates the catching device shown in FIG. 1, in plan view, omitting the part of the safety binding shown in FIG. 1;

FIG. 3 is a perspective view of a further embodiment of the catching device according to the present invention adapted for use with a heel-type safety binding and illustrating the catching device in its actuated or catching position;

FIG. 4 is a further embodiment of the catching device according to the present invention adapted for use with a cable-type safety binding;

FIGS. 5 and 6 illustrate a locking apparatus for the 60 catching device;

FIG. 7 is a still further embodiment of the catching device according to the present invention;

FIG. 8 is a cutaway view, partly in section, of the 65 catching device of FIG. 7 (in its skiing position); and

FIG. 9 is a cutaway view, partly in section, of the catching device of FIG. 8 in its stopping or catching position.

DESCRIPTION OF THE PREFERRED EMBODIMENT

With reference to FIGS. 1 and 2 it is seen that a yoke 1 with its end portions is rotatably mounted on the ends of a fulcrum means, such as a shaft or axle 2 which in turn extends transverse with respect to the upper surface of a ski 3. The axle 2 is placed in a cylindrical housing 4 to which there is secured a mounting plate 5. With the help of the mounting plate 5 the entire catching device is secured to the upper surface of the ski 3 preferably by means of screws 6.

The type of binding shown in FIG. 1 comprises a base plate 31 securely connected to a ski boot 30, and is releasably journaled at its front and back portions in binding heads 32 and 33. The mounting plate 5 is mounted together with the back head 33 of the binding. The yoke 1 is then lying under the base plate 31 and will be pressed down by the base plate 31 into its inactive or rest position, as shown in FIG. 1.

The yoke 1 extends from its pivot point on axle 2, as seen in FIGS. 1 and 3, into a pair of widened portions 7 which are protruding rearwardly in the rest position shown in FIGS. 1 and 2 and downwardly in the operating or catching position as shown in FIG. 3. Such widened portion 7 on each side is extended in the form of a shank portion 8.

With reference to FIG. 2 it is seen that a torsion spring 9 is mounted in a housing 4. The torsion spring 9 can be, for example, made in the form of a helical spring. At one end the torsion spring 9 is coupled with a tensioning disc 10 which is mounted adjacent the housing 4 and is coaxial with respect thereto. This tensioning disc 10 is provided on its circumferential surface with apertures 11 into which an appropriate instrument can be inserted and thereby cause rotation of tensioning disc 10 with the consequential result of adjusting the bias force of the spring 9 to a desired strength.

On the housing 4 at one end thereof a boss 12 is provided against which a projection 13 provided on yoke 1 abuts, such projection being provided with a spring bolt 14 which comes in actual abutment with boss 12 when the yoke 1 is moved into the catching position. A similar boss can also be provided at the other end of the housing 4 thereby to afford that yoke 1 could abut at both its ends.

The catching device according to the present invention in its operative or rest position is arranged in such a manner, as seen in FIGS. 1 and 2, that yoke 1 and its shank portion 8 lie parallel with the longitudinal edge of ski 3 and do not interfere with its sliding movement. In this position yoke 1 protrudes from axle 2 and also from housing 4 in a forward direction and thereby it lies under the ski boot 30 or in the event type binding is used as shown in FIG. 1, using a base plate 31, it will lie under base plate 31. In the event of a fall when the safety binding opens and the ski becomes loose from the foot of the skier, the torsion spring 9 will rotate yoke 1 and its shank portions 8 into the catching position shown in FIG. 3 in which the yoke 1 points in a substantially vertical direction with respect to the ski 3 and the shank portions 8 point in a substantially vertical direction downward with respect to ski 3. As particularly can be seen in FIG. 3, as a result of the opening of the catching device according to the present in-

vention, the ski at the point where the catching device shank portions are, becomes completely relieved of its own weight which has been before distributed on the running surface of the ski, that is a good portion of the total weight of the ski is distributed under relatively hard snow conditions (packed slope) on the narrow supporting edges 15 of both shank portions 8. As a result the surface pressure becomes substantially increased and the shank portions 8 dig themselves somewhat into the snow during the movement of the released ski and bring them to a stop in a short period of time. In the event of a loose deep snow into which the ski easily sinks even under its own weight, the upwardly pointing yoke portion 1 will pile up the snow in front of it so that this braking action will assist a restraining of the runaway ski in a short time and on a short distance. The embodiments of the catching device according to the present invention are substantially the same when used with the safety binding types illustrated in FIGS. 1 and 3 and the sole difference between these two embodiments amounts only to different dimension of the yoke 1. The yoke 1 comprises a pair of arm portions 16 and a connecting plate portion 17 which together with both arms 16 forms a single piece. The two arms 16, as seen in FIG. 3, have an angular cross section in order to provide a better stiffening of yoke 1. Arms 16 must have a length in the embodiment shown in FIG. 1 which assures that the connecting plate 17 after the device has been rotated in the catching position will not interfere with the head 33 of the safety binding which rather will fall within the window formed by arms 16 and connecting plate 17.

According to the present invention the connecting plate 17 of the yoke 1 is provided with a projection 19 which is especially beneficial when used in connection with the binding according to FIG. 1. During the release a rotational movement of the foot with respect to the ski 3 takes place and such rotational movement could be prevented or interfered with by the friction arising between the spring biased yoke 1 and the ski boot 30 or base plate 31. By the provision of projection 19 the base plate 31 or the ski boot 30 and the yoke 1 become isolated from each other with the exception of the small contact surface of projection 19. For this purpose projection 19 is provided in the center of the rotational movement, namely in about the center of the last portion of the boot.

The embodiment shown in FIG. 3 is preferred to be used with the heel-release type safety bindings in which the ski boot (not shown) is held down by a heel-release device 18, particularly with a fork portion 18a thereof (both portions being shown with a dashed line in order to avoid crowding of the drawing) which during a fall moves rearwardly and releases the ski boot. For this type of binding it is preferable that the mounting plate 5 extends opposite to that shown in FIGS. 1 and 2, that is rearwardly, so that it can be mounted on the ski 3 together with the heel-release unit 18. This can be done without difficulty since it is necessary only that the housing 4 be rotated by 180° when placed into yoke 1, then boss 12 can be placed into its position. A placing of the catching device behind the heel-release unit 18 would be difficult because of the presence of reset lever 20 and it would be necessary to make arms 16 extremely long. It should also be considered in connection with

this type of binding that it is advantageous to place the catching device as near as possible to the center of gravity of the ski and thereby to attain the largest possible braking, that is catching effect.

The above-described embodiment cannot be used with cable or pull-type safety bindings since arms 16 partially overhang on the side of the ski as seen in FIGS. 1, 2 and 3. If used with cable-type safety bindings, the arms 16 would interfere with the region of the cable lug 21 for cable 22. It is, therefore, necessary to employ another embodiment of the catching device in which the yoke 1a comprises substantially a plate 17a which is connected rotatably to axle 2 by means of a pair of short offset arms 16a. The plate 17a is preferably made as long that it will lie at least with a portion thereof under the last portion of the ski boot, and should be made as wide as the ski in order to avoid any interference with the cable. Also, in this case it is preferred to have a projection 19 described above placed on plate 17a as shown in FIG. 4 for the purposes described.

For locking of the catching device during transporting of the skis a device shown in FIGS. 5 and 6 is preferred according to the present invention. Such locking device comprises a pair of cylindrical stems 40 to be used with both skis. A chain or plastic rope 41 connects both stems 40 together and thereby it will couple both skis together so that the skier will be reminded to remove the locking device from the ski and thereby set the catching device on before the first run. Each stem 40 has a pair of grooves 42 on it having a distance between them corresponding to the distance between the two shank portions 8 and the width of such grooves 42 corresponds to the thickness of the shank portions 8. The catching device is placed into the position shown in FIG. 1 and one of the stems 40 is inserted into aperture 43 shown in FIG. 3 provided in shank portions 8 and is shoved transversely over the ski 3. Both shank portions 8 are forced under the action of the spring 9 into grooves 42 to prevent a sliding out of the stems 40.

Another device shown in FIG. 6 serves for a short blocking of the catching device during the mounting of the skis. Such device shows a short pin 44 which is inserted into one of the apertures 43 and becomes arrested in groove 42. The pin 44 is connected with a plate 45 which has also an abutting surface 46 thereon which in turn abuts against the upper smaller side of the shank portion 8 and serves to hold it in position in which it protrudes beyond the under side of the ski and serves to remind the skier that the device should be removed before the first run and that the catching device should be set.

A further preferred embodiment of the present invention is shown in FIG. 7. In this embodiment both shank portions 8 do not form a single piece with yoke 1, but they are also rotatable not only about the axle 2 but also about the yoke 1 itself. The yoke 1 instead of having connecting plate 17 on arms 16, is made from a round profile material and on both of its sides is made in the form of a shaft 50. About this shaft, each shank portion can be rotated into a position in which it forms an angle with the longitudinal axis of the ski which angle is opened toward the head of the ski. The shank portions 8 also somewhat converge backwardly which

results in a better braking effect since the snow will be piled up against the ski. In the arrested position both shank portions 8 lie on the upper side of the ski and are in flush with the upper edge thereof. In order that they could be swiveled into the catching position, it is preferred that on each ski edge a slide block 51 is provided so that the shank portions 8 could slide downward over these blocks. The shank portions 8 for this purpose are provided with a downward chamfering angle 52. Each yoke 1 is further provided with an angular portion 54 which during the resetting of the catching device into its flat or rest position abut against a boss 55 provided on the ski. As a result, portions 54 becomes forced upward so that the shank portions 8 become securely abutting against the ski after a slight rotational movement about the axis 50.

I wish it to be understood that I do not desire to be limited to the exact details of construction shown and described, for obvious modifications will occur to a person skilled in the art.

Having thus described the invention, what I claim as new and desire to be secured by Letters Patent, is as follows:

1. A catching device, for use in connection with a ski having an upper surface, two sides, and a lower running surface extending in one direction and operative to prevent the ski from running away upon becoming loose from the boot of the skier, comprising in combination,

means establishing a fulcrum on said ski,
yoke means adapted to be mounted for rotation about said fulcrum, said yoke means having a shank portion extending beyond said fulcrum at both sides of the ski and a yoke portion held in engagement with the upper surface of the ski by the boot of the skier,

and spring means biasing said shank portion in a direction transverse to said one direction and operable for pointing said yoke portion upwards from said upper surface and said shank portion downwards from said running surface when the boot is released from the ski, said fulcrum means including a rotatable axle, said yoke means being connected to said axle, said spring means including a helical spring mounted on said axle, and means for adjusting the tension of said spring means.

2. A catching device as claimed in claim 1, wherein said yoke portions comprises a pair of arm portions extending away from said axle in a direction opposite said shank portion and a connection portion interconnecting said arm portions at their end portions further from said axle and forming a window with said arm portions and said axle, said connecting portion, when said device is mounted on a ski, adapted to be flat on the upper surface of the ski.

3. A catching device as claimed in claim 1 further including a housing for receiving said axle and said spring means, whereby said adjusting means mounts said spring means in said housing.

4. A catching device for use in connection with a ski having an upper surface, two sides, and a lower running surface extending in one direction and operative to prevent the ski from running away upon becoming loose from the foot of the skier, comprising in combination,

means establishing a fulcrum on said ski,

yoke means adapted to be mounted for rotation about said fulcrum, said yoke means having a shank portion extending beyond said fulcrum at both sides of the ski, and spring means biasing said shank portion in a direction transverse to said one direction and pointing downwards from said running surface, said fulcrum means including a rotatable axle, said yoke means being connected to said axle, said spring means including a helical spring mounted on said axle, and means for adjusting the tension of said spring means, said yoke means further including a pair of arm portions extending away from said axle in a direction opposite said shank portion and a connection portion interconnecting said arm portions at their end portions further from said axle and forming a window with said arm portions and said axle, said connecting portion, when said device is mounted on a ski, adapted to be flat on the upper surface of the ski, and a projection provided on said connecting portion pointing in an upward direction away from the top surface of a ski when said device is mounted and adapted to abut against the sole of a boot when in skiing position.

5. A catching device in combination with a ski mounted thereon for preventing its running away after becoming loose from the foot of the skier comprising an axle mounted transversely on said ski over the top surface thereof; yoke means fixedly mounted on said axle for rotation therewith and having a pair of shank portions extending beyond and away from said axle;

spring means biasing said axle and thereby said shank portions in a direction substantially transverse to the top surface of said ski; said shank portions being adapted to lie flush against each side of said ski when said yoke means is biased against the face of said spring means when said boot is in skiing position, said shank portions leaving a clearance above the bottom surface of the ski, said yoke means lying flat against the top surface of the ski when said boot is in said skiing position, and a boss means provided on said yoke means for abutting against the sole of a boot and spacing said yoke means therefrom.

6. A catching device for use in connection with a ski 15 and operable for preventing its running away after becoming loose from the boot of the skier, comprising an axle adapted for being mounted transversely on said ski over the top surface thereof; yoke means fixedly mounted on said axle for rotation therewith and having a yoke portion thereof held in engagement with the upper surface of the ski by the boot of the skier and free end portions thereof extending beyond and away from said axle; a pair of shanks rotatably mounted on respective end portions of said yoke means, and spring means biasing said axle and thereby said yoke means into a catching position away from the top surface of said ski and simultaneously rotating said shanks about longitudinal axis of said free end portion of said yoke means into an open angular position with respect to the tip of the ski.
